UNITED STATES PATENT OFFICE

2,190,611

MACHINE FOR APPLYING WEAR-RESISTANT PLATING

Gustav Sembdner, Berlin-Tempelhof, Germany

Original application February 23, 1938, Serial No. 192,178. Divided and this application August 9, 1938, Serial No. 223,911. In Germany November 23, 1935

11 Claims. (Cl. 29—33)

This invention relates to metallic parts having improved wear-resistant surfaces, and more particularly to apparatus for manufacturing such parts with wear-resistant surface layers incorporated therein.

5 This application is a division of my copending application Serial Number 192,178, filed February 23, 1938, for "Wear-resistant plating." Shown in that application are various structures embodying wear-resistant surfaces in accordance 10 with my invention, including wheels for rail vehicles, pulleys, bars and the like.

One of the objects of my invention herein described is to provide a machine for applying wear-resistant layers to wheels in the manner disclosed 15 in my application Serial Number 192,178.

Another object of my invention is to provide means for adapting existing machines to the purpose of applying wear-resistant layers to 20 wheels.

Still another object of my invention is to provide preadjusted guide means and preformed roller means in combination with a wheel set lathe for applying wear-resistant strips to wheel rims, 25 the strips being passed through the guide means and pressed by the roller means into secured position on the wheel rims.

A further object of my invention is to provide heating means for the strips in connection with 30 or above the guide means therefor, and quenching means below the roller means for hardening the strips after they are secure in the wheel rims.

A still further object of my invention is to provide lateral clearance compensation means between 35 the roller means and the wheel flange to correct for clearances due to different thicknesses of the flanges on the wheel rims.

I incorporate into the surfaces of metallic parts which are subjected to heavy stresses and wear 40 and tear separate layers of a material having substantially higher resistance against wear and tear than the metallic part to be improved. In the practice of my invention I force a wear-resistant plating in the form of a plate or strip into 45 recesses of the surface to be improved, by a cold or preferably hot hammering, rolling or pressing operation. The recess in the metallic part to be improved is preferably undercut or "backed off", for instance, in the form of a dovetail groove or 50 recess which is engaged by the wear-resistant plating when it is forced into the recess and deformed.

The wear-resistant plates or bands are formed with a curved or arched convex cross section so 55 that there remains clearance in the middle be-

tween the metallic part and the wear-resistant plate which clearance renders it possible to depress and flatten the wear-resistant plates, whereby their lateral edges are deformed and project and engage or intermesh with the undercut faces.

I may incorporate the wear-resistant plates into the metallic parts or supports by cold working, but generally, I prefer to heat the wear-resistant material to facilitate its deformation without changing its inner structure. I have found that red hot temperature of the wear-resistant material is very favourable for the pressing and deforming operation. Also, it is thus possible to harden the wear-resistant material by quenching 15 it immediately following the rolling, forging, hammering or pressing operation.

The metallic part or support may be iron or any other metal which is capable of forming a support for tightly securing the wear-resistant 20 plating. The wear-resistant plating may be steel which is improved or alloyed in any known manner, for instance, manganese steel containing 12—14% manganese, steel containing chromium and nickel or vanadium. Other than steel alloys 25 may also be used, for instance, metals of the hard metal group, such as tungsten, carbide or the like. Furthermore, where the wear is due to chemical attacks, platings or anti-corrosive or 30 non-rusting material may be employed. The coefficient of thermal expansion or heat elongation of the wear-resistant material should be at least approximately similar to the corresponding coefficient of the metallic support.

35 My invention offers special advantages in connection with wheels for rail-vehicles. As is well known, the bearing or running surface and the flange of such wheels are heavily stressed and worn out very soon. My invention renders it 40 possible to use such wheels for a much longer period of time, by incorporating wear-resistant material in the flanges or tires or all over the running surface of new wheels or wheels which are to be repaired, without changing the wheel 45 diameter.

A special advantage of my novel fastening system lies in the fact that the wear-resistant material can be easily applied or incorporated and when it is worn out, can be easily removed and 50 interchanged, by means of simple or existing devices.

The invention will be better understood by reference to the following detailed description in connection with the accompanying drawings 55

showing by way of example and schematically some embodiments of the invention, viz.:

Fig. 1 is a fragmentary cross section of the rim or tire of a wheel for rail vehicles, provided with 5 a wear-resistant plating according to the invention.

Fig. 2 is a fragmentary cross section showing a method of inserting the wear-resistant plating.

Figs. 3 and 4 are further fragmentary cross sections of the rim of a wheel for rail vehicles, having 10 the invention applied thereto.

Figs. 5 and 6 are a fragmentary cross section and a longitudinal section of a device for rolling a wear-resistant plating into the surface to be 15 improved.

Fig. 7 is a schematic view of an arrangement for heating, rolling in and quenching wear-resistant bands in wheels for rail vehicles.

Fig. 8 is a side view, partly in section, of Fig. 7. 20 Fig. 9 is a schematic plan view, partly in section, of a rolling device.

Fig. 10 is a perspective view of an arrangement for rolling-in wear-resistant strips in railway wheels, adapted for use with an ordinary wheel 25 set lathe.

Fig. 11 is a side elevation of the arrangement shown in Fig. 10.

Fig. 12 is a front elevation of the same arrangement. 30

Fig. 13 is an elevation of a detail of the machine shown in Figs. 10 to 12.

Fig. 14 is a plan view of the parts shown in Fig. 13.

Various embodiments of wheels for rail vehicles, as used in railway cars or tramway cars, are shown in Figs. 1 to 4. As is well known, 35 the running surfaces of such wheels are subjected to many different stresses and have to be corrected as to their cross section at regular 40 intervals. Now, I provide those portions of the cross section of the rim which are mostly stressed and worn out with a plating or insert of a material offering extremely high resistance against 45 these stresses and wear and tear, whereby the wheels may be used for a much longer time until correction and machining is again required. Moreover, when the cross section of the rim is 50 worn down to the admissible limit, my novel system of fastening the wear-resistant plating to the wheel surface renders it possible to interchange or replace the wear-resistant plating in a simple manner, as will be hereinafter described.

Figs. 1 and 2 show the cross section of a tire 55 of a railway wheel having its mostly stressed portion at 12. In order to protect the wheel against wear, I cut a groove or recess into said portion 12 having undercut flanks 13 and 14. Now a strip 15 of a material offering a very high resistance against wear is hammered, forged, 60 pressed or rolled into said groove, whereby it is securely and intimately connected with the rim. The wheel may now be used until the admissible lower limit of the cross section of the rim is reached. In this case the wear-resistant strip 15 is usually also worn out to such an extent 65 that a new wear-resistant strip or insert has to be applied. To this end, the wheel rim is turned down to the smaller standard cross section 16. It is not necessary in this turning operation to 70 turn the whole rim down to the lowest point of the worn flank 12 of the wheel flange, since a groove 17 having undercut flanks 18, 19, is turned into this flank, into which a strip similar to the strip 15 in Fig. 1 is forced. As shown in Fig. 2, 75 the strip is at first S-shaped so that it can be

inserted into the groove 17. After the strip 15 has been inserted, it is stretched in the groove, by means of a roller 15', in the manner herein-after described. It will be understood that instead of a narrow groove and strip as shown in 5 Figs. 1 and 2, a wider groove and strip may be used, so as to cover practically the whole running surface of the wheel.

Further manners of fastening the wear-resistant plating on the wheel rim are shown in Figs. 10 10 and 4, illustrating two dovetail grooves 21, 21' and 22, 22' into which a suitably curved and arched strip 43 is inserted, the initial shape of which is shown in Fig. 3. This strip 43 is rolled and deformed as shown in Fig. 4 to form a 15 smooth running surface together with the wheel rim.

Generally, there is a very small clearance only 20 between the groove or recess and the wear-resistant material inserted in the recess; therefore, water or other aggressive substances will not 25 usually be permitted to enter into the groove. Where it is intended to protect the groove additionally against corrosion, the surface of the groove and/or the inwardly directed surface of the wear-resistant material may be provided with an anti-corrosive or non-rusting coating which 30 may be very thin, since it is protected against mechanical injuries by the wear-resistant strip. In Fig. 3 a coating 42 of anti-corrosive has been indicated on the surface of the recess which 35 coating may be applied by a galvanic process, by a spreading process or by a metal spraying process. A similar coating 43 is shown on the inner face of the wear-resistant strip in Fig. 3. Where the strip is not heated in the attaching 40 operation, this coating may be applied in the same manner as the coating 42; where the strip is attached in hot condition, a coating of a refractory or fire-proof material has to be applied.

The provision of a protective coating between the wear-resistant material and its support is an important feature of my invention. More particularly this coating renders it possible to ensure a reliable and durable metallic contact 45 between the wear-resistant material and its support which contact is important, for instance, in case of wheels for rail-vehicles or slide contacts intended to transmit electric current from the rail to the wheel or slide contact. Moreover, 50 I have found that the said protective coating forms a bar for the flame of a cutting torch so that the surface of the groove is not impaired or injured by the cutting flame.

In some instances when the wear-resistant 55 strip is rolled into the recess of its support with a corresponding increase in width, the portion of the strip shortly prior to the rolling station tends also to become wider, whereby difficulties arise in inserting the strip into the recess. In 60 Figs. 5 and 6, 44 is the band or strip to be inserted and is arched as at 45. The support is provided with a dovetail groove 46 into which the wear-resistant strip is forced by means of a roller 47. Now, I have found that the strip 44 65 tends to flatten prior to the point where it is depressed by the roller 47, whereby its exterior edges may overlie the groove. In order to avoid this defect, I guide the strip 44 through a guiding device, as shown in Figs. 5 and 6, which is 70 adapted to the width of the strip and prevents flattening of the strip outside the groove, and ensures at the same time a smooth rolling operation. As will be seen in Figs. 5 and 6, guiding members 50, 50', 50'', 50''' are provided in front 75

of the roller 47 for guiding the strip. It will be understood that the guiding members 50, 50', 50'', 50''' may be constructed in the form of a single unitary device.

5 Figs. 7 and 8 illustrate by way of example and schematically the rolling operation applied to a rail wheel of the kind shown in Figs. 1 and 2. The wear-resistant strip of convex shape is guided through a heating device 52, for instance, a muffle furnace, and pressed into the groove 54 of the wheel rim by means of the roller 53, the cross section of which corresponds to the flank of the flange of the wheel. The finished strip 51 can be hardened by means of a quenching device 55 10 in the form of a water spraying nozzle or the like. A modified form of the roller is shown in Fig. 9, illustrating a roller 56 which is provided to roll a wear-resistant strip 57 into the groove 58 of a rail wheel 59, so as to improve the running surface and the flank thereof. It will be understood that a roller of the shape shown in Fig. 9 may also be used in the device shown in Figs. 7 and 8, instead of the roller 53. Various forms of joints of wear-resistant strips are shown 15 25 in my copending application Serial Number 192,178, hereinbefore referred to. It will be understood that the construction and form of the joint depends on the stress to which the respective metallic part is subjected in operation.

30 It will be understood that my novel principle can be applied not only to existing wheels for rail vehicles having separate tires, as for instance, illustrated in Fig. 8, but the invention especially permits of the manufacture of wheels 35 having no tire at all, but having simply a grooved rim into which the wear-resistant strip is rolled, as indicated in Fig. 3. In this case the wear-resistant strip can be removed from the wheel and replaced by a new one when it is worn out.

40 Generally, any suitable rolling machine or apparatus may be used to apply the wear-resistant material to its support, but in case of round metallic parts, more particularly wheels, I prefer to employ ordinary wheel set lathes reconstructed 45 or modified to meet the purpose in question. By way of example, Figs. 10-14 show a device of this kind, comprising a face plate or disc 71 of a wheel set lathe and a base plate 72 for the slides. The wheel set 73, one wheel of which 74 has been 50 shown only, for the sake of clarity, is inserted or chucked in the usual manner, preferably in such a way that the axle stub 75 of the wheel set rotates on the center 76 of the face plate 71 while the wheel set is rotated in usual manner, for instance, by drivers from the opposite plate which is not shown in the drawing. The two slides are removed from the plate 72 and replaced by a device 77 (Fig. 11) by which the strip 78 can be rolled into the groove 79 of the 55 wheel. The strip 78 passes through a guiding device 80 which, as already mentioned, may receive the heating device for the strip at the same time.

60 The device 77 comprises a roller 81 which has a cross section corresponding to the profile or cross section of the wheel. This roller 81 is guided in a fork-shaped frame 82 terminating in a rod 83 (Figs. 13 and 14) which is adjustable in the anchor plate 85 by means of a screwing device 84, so that the roller 81 is supported by this 65 anchor plate 85. The plate 85 in turn is relieved from the forces thus acting upon it by brackets 87, 87' (Fig. 12) surrounding the axle 73 of the wheel set and the emergency running surface 86 or the axle stub 75 of the wheel 74, 70 and connected by tension rods 88, 88' to the 75

anchor plate. The plate 85 is thus quasi "suspended" from the axle of the wheel. Rollers 89 are provided in the bracket 87 and rollers or slide bodies are provided in the bracket 87'. In this manner the roller 81 can be adjusted to exert the desired pressure by means of the screwing device 84 which advantageously is connected with the rod 83 by a ball and socket joint.

75 The roller 81 due to the different thicknesses of the flanges or tires 90 will sometimes have a lateral clearance with respect to the said tire or flange 90 which should be advantageously limited or entirely eliminated. To this end I provide a circular disc 91, the shaft 92 of which is inclined with respect to the shaft of the roller 81 and the surface 93 of which is wedge-shaped so as to engage the space between the tire 90 and the roller flange 81'. It will be understood that the play or clearance between the tire 90 and the roller 81 can be easily changed or eliminated by moving or pressing the disc 91 more or less into this interspace, by means of the screwing device 94.

80 The disc 91 is supported on the bracket 95 which may be secured to the fork 82 by means of screws. According to another modification of the invention the clearance between the tire and the roller may be eliminated by providing the roller 81 with interchangeable or adjustable lateral flanges 81', as shown in Fig. 14. Also the clearance between the roller 81 and the tire may be eliminated by means of lateral pressure rollers (not shown) or the like.

85 Provided at 96 between the guide plate 80 and the flange 90 in Figs. 10 and 14 is the guiding device for the strip 78 which has been hereinbefore described with reference to Figs. 5 and 6; the shape of this device is adapted to the profile or cross section of the groove and strip.

90 It will be understood that the machine operates in such a manner that the wheel set 73 rotates in a counter-clockwise direction, whereby the strip 78 is pressed into a groove of the wheel 74 under action of the pressure exerted by the roller 81. The groove portion of the wheel and the portion of the strip already rolled-in pass through a container 97 filled with a suitable quenching agent, as for instance, water or oil or a salt solution. Alternatively, a squirting device 95 may be provided as in Fig. 7.

95 While I have herein shown and described certain preferred embodiments of my invention, I wish it to be understood that I do not confine myself to all the precise details herein set forth by my way of illustration, as modification and variation may be made without departing from the spirit of the invention or exceeding the scope 100 of the appended claims.

105 What I claim as new and desire to secure by Letters Patent of the United States is as follows:

1. In a machine for embedding a strip of wear-resistant material in a recess in the running surface of a wheel, means for supporting and rotating the wheel, means adjacent the wheel for heating the strip of wear-resistant material, means adapted to engage the running surface of the wheel in close proximity to said heating means for rolling said strip into the recess of the wheel, and means disposed in operative relation to said wheel for quenching said strip after the 110 rolling operation.

115 2. In combination with a wheel set lathe, for mounting on the slide of said lathe, a device for embedding a strip of wear-resistant material in a recess in the running surface of each wheel of

- a wheel set in said lathe, said device comprising means disposed adjacent one of the wheels for heating a strip of wear-resistant material, and means mounted in close proximity to said heating means and adapted to engage the running surface of said wheel for rolling said strip into the recess of said wheel.
3. In combination with a wheel set lathe, a device as set forth in claim 2 and including means disposed in operative relation to said wheel for quenching said strip in its embedded position in said recess.
4. In a machine for embedding a strip of wear-resistant material in an undercut recess in a machine part, means for forcing said strip into said recess and extending said strip laterally into intimate bound relation with said machine part, and means in close proximity to said part and the aforesaid means for guiding said strip and preventing lateral extension thereof immediately exterior of said recess.
5. In a machine for improving the running surface of flanged wheels, a roller adapted to engage said running surface and having flanges embracing the sides of said wheel, and a second roller having a wedge shaped rim portion adjustably engageable between the flange of said wheel and the coacting flange of the first said roller for maintaining said wheel and the first said roller in relatively fixed operative relation.
6. In a machine for embedding a strip of wear-resistant material in a recess in a machine part, means for heating the strip, and means in close proximity to said heating means for forcing the heated strip into the recess in said machine part.
7. In a machine as set forth in claim 6, the combination therewith of means for quenching the heated strip in its embedded position in said recess.
8. In a machine as set forth in claim 6, the combination therewith of fluid discharge nozzle means disposed in operative relation to said machine part for quenching the heated strip subsequent to the operation of the second said means.
9. In combination with a wheel set lathe having a wheel set mounted therein, a device for applying pressure on the running surface of a wheel of said wheel set comprising a yoke structure connected with said lathe and having arm members engaged with said wheel set on opposite sides of said wheel thereof, a roller mounted in said yoke structure and disposed in engagement with the running surface of the said wheel, and means for adjusting the pressure of said roller with respect to said wheel and the corresponding tension in said arm members.
10. In a machine for embedding a strip of wear-resistant material in an undercut recess in the running surface of a wheel, means for supporting and rotating the wheel, means for heating the strip of wear-resistant material, guiding means for conducting the heated strip to said undercut recess and preventing lateral extension of said strip exterior of said recess, and roller means for forcing the heated strip into said recess and extending said strip laterally into intimate bound relation with said wheel.
11. In a machine as set forth in claim 10, the combination therewith of means for quenching said strip in its embedded position in said recess.

GUSTAV SEMBDNER.
